UNITED STATES PATENT OFFICE.

CARL ARNOLD, OF NUEREMBERG, GERMANY.

ILLUMINATED SPINNING TOP.

Application filed November 19, 1927, Serial No. 234,471, and in Germany March 30, 1927.

A spinning-top has become known in which sparks, produced by a spark-producing device, become visible through windows in the wall of the top, which have colored 5 transparent panes, so that the sparks are seen through the circulating colored transparent panes as coming and disappearing comet-like phenomena. In illuminated spinning-tops of this type the spark-producing 10 disk, fixed on a vertical axle, rotates.

The invention consists in that the cerium-stone-mechanism serving to produce the spark-brushes engages with the top part of the spinning top so that it is rotated, the 15 emery-disk with a hollow support being mounted in the bottom-part of the spinning top in such a manner that it remains relatively fixed and rotates at slower speed than the spinning top. By this arrangement star-like spark-groups are produced which are 20 visible through the transparent panes.

An embodiment of the invention is illustrated, by way of example, in the accompanying drawing in which:

25 Fig. 1 is a section, partly in elevation,

Fig. 2 shows the bottom-part of the spinning top in plan-view.

Fig. 3 shows in a view from below the holding arm for the transparent panes.

30 Fig. 4 shows how the plate *i* is mounted on the arm *r*.

The spinning top consists of a casing composed of a bottom-part *a*, and of a top-part *b*, a winding up pin *c* being rigidly connected 35 with the casing. In the top-wall of top-part *b* several windows *d* are arranged which are covered from below by transparent panes *f*, designed to produce colored light-effects.

These colored transparent panes *f* are not 40 fixed on the inner surface of the top-part *b* but on radial holding arms *t* by means of flaps *u*.

These radial holding arms *t* are securely held by flaps *v*, stamped out of the top *s* of the spinning top and adapted to be 45 folded over (Fig. 3). In the top-part *b* of the casing a slightly conical sleeve *g* is fixed which has apertures *h* is its bottom-plate. Flaps *k*, stamped out of a horizontal disk *i* which is rotatably mounted on pin *c*, are 50 bent upward at right angles and project through these apertures *h* so that the disk *i* rotates when the spinning top is being rotated.

Flaps *l* bent downward at right angles are further stamped out of disk *i* 55 and the ends of oscillatable levers *m*, carrying on the lower surface of their outer

end each a cerium stone *n*, are oscillatably mounted in said flaps *l*. In the lower part *a* of the casing of the spinning top a friction-disk *o*, on the upper surface of which a ring-shaped-disk *q* of emery paper is stuck, carries the downwardly directed hollow foot *p* of the spinning top. This friction-disk *o* is mounted in a manner so as to remain relatively fixed.

The operation is as follows: When the spinning top is being rotated by a winding up mechanism the arms *k*, projecting into sleeve *g* of the spinning top, move with the spinning top and rotate the horizontal disk *i* with the oscillatable levers *m* which carry the cerium-stones *n*. By the friction exerted by the cerium-stones *n* on the emery-disk *o*, this emery-disk *o* with the foot *p* are rotated at slower speed than the spinning top, so that the sparks which are produced are broken up into star-like formations which are visible through the colored transparent panes *f* under the windows *d*. In order to prolong the production of star-shaped colored spark-formations a disk *r* of heavy material is mounted on the emery-disk *i*.

To interchange the colored transparent disks the top-part *a* of the spinning top casing has to be removed and the flaps *v* holding the radial arms *t* in the top-portion *s* of the spinning top have to be bent upward so that the holding arms *t* with the transparent panes *f* can be removed and other transparent panes inserted.

The toy becomes more interesting by this arrangement.

The spinning top as well as the several elements of the same may be of other shapes 95 as those described and shown without departing from the scope of the invention. The interchangeable holding arms may also be constructed in another manner, as well as the fixation means.

I claim:—

1. An illuminated spinning top, comprising in combination a casing composed of two parts, a top part having windows in its top wall and a bottom-part to which said top part is detachably connected, a top fixed on the centre of the top-part of the casing, a winding up device in said casing and extending at the top and bottom-end from said casing, a horizontal disk in said casing rotatably mounted on said winding device, flaps stamped out of said horizontal disk and

bent downward at right angles, arms stamped out of said horizontal disk and bent upward at right angles, an emery disk mounted in a manner so as to remain relatively fixed, a hollow foot downwardly projecting from the centre of said emery-disk and projecting from the lower end of said casing, oscillatable radial levers pivotally mounted in said downwardly bent flaps of said horizontal disk, a cerium-stone fixed on the lower surface near the free end of each oscillatable lever and resting on said emery-disk, a downwardly projecting sleeve fixed in the top-part of said casing and having 10 apertures in its bottom-plate through which said upwardly directed arms of said horizontal disk project, and means for interchangeably mounting transparent panes under said windows in said top plate of the 15 top-part of said casing.

2. An illuminated spinning top, comprising in combination a casing composed of two parts, a top-part having windows in its top wall and a bottom-part to which 25 said top part is detachably connected, fixed on the centre of the top-part of the casing, flaps stamped out of the lower end of said top, radial holding arms, held by said folded down flaps, a colored transparent pane removably fixed on the upper surface of each radial lever so that it covers from below the corresponding window in said casing, a winding up device in said casing and extending at the top and bottom-end from 30 said casing, a horizontal disk in said casing rotatably mounted on said winding device, flaps stamped out of said horizontal disk and bent downward at right angles, arms stamped out of said horizontal disk and bent upward at right angles, an emery disk 35 mounted in a manner so as to remain relatively fixed, a hollow foot downwardly projecting from the centre of said emery-disk and projecting from the lower end of said casing, oscillatable radial levers pivotally mounted in said downwardly bent flaps of said horizontal disk, a cerium-stone fixed on the lower surface near the free end of each oscillatable lever and resting on said emery-disk, a downwardly projecting sleeve fixed 40 in the top-part of said casing and having apertures in its bottom-plate through which 45 said upwardly directed arms of said horizontal disk project, and means for interchangeably mounting transparent panes under said windows in said top plate of the 50 top-part of said casing.

said upwardly directed arms of said horizontal disk project, and means for interchangeably mounting transparent panes under said windows in said top plate of the 55 top-part of said casing.

3. An illuminated spinning top, comprising in combination a casing composed of two parts, a top-part having windows in its 60 top wall and a bottom-part to which said top part is detachably connected, a top fixed on the centre of the top-part of the casing, flaps stamped out of the lower end of said top, radial holding arms, held by said folded down flaps, flaps stamped out of each of said radial holding arms adapted to be folded down to removably fix a transparent colored pane, a colored transparent pane removably fixed on the upper surface of each radial lever so that it covers from below the corresponding window in said casing, a winding up device in said casing and extending at the top and bottom-end from 65 said casing, a horizontal disk in said casing rotatably mounted on said winding device, flaps stamped out of said horizontal disk and bent downward at right angles, arms stamped out of said horizontal disk and bent upward at right angles, an emery disk 70 mounted in a manner so as to remain relatively fixed, a hollow foot downwardly projecting from the centre of said emery-disk and projecting from the lower end of said casing, oscillatable radial levers pivotally mounted in said downwardly bent flaps of 75 said horizontal disk, a cerium-stone fixed on the lower surface near the free end of each oscillatable lever and resting on said emery-disk, a downwardly projecting sleeve 80 fixed in the top-part of said casing and having apertures in its bottom-plate through which said upwardly directed arms of said horizontal disk project, and means for interchangeably mounting transparent panes under 85 said windows in said top plate of the top-part of said casing.

4. In a top as specified in claim 1, a centrifugal disk on said horizontal disk for assisting the rotating movement of said horizontal disk.

In testimony whereof I affix my signature.

CARL ARNOLD.
